UNITED STATES PATENT OFFICE.

THOMAS E. MURRAY, OF BROOKLYN, NEW YORK

FUSE-SWITCH MECHANISM.

Application filed April 26, 1922. Serial No. 556,818.

To all whom it may concern:

Be it known that I, THOMAS E. MURRAY, a citizen of the United States, and resident of Brooklyn, county of Kings, and State of New York, have invented certain new and useful Improvements in Fuse-Switch Mechanism, of which the following is a specification.

The invention relates to a switch mechanism and casing therefor, the whole arranged so that when access is provided to the terminals, for insertion of a fuse or for other purposes, the current is broken and when the circuit is closed the fuse terminals or the like are covered; and so that other relative arrangements of the parts may be achieved, all as described in the following specification and covered in the claims.

The accompanying drawings illustrate embodiments of the invention.

Figs. 1 and 2 are perspective views illustrating respectively the closed and the open position of the switch;

Fig. 3 is a horizontal section through the casing with the mechanism therein shown in plan;

Fig. 4 is a longitudinal section through the same;

Fig. 4^a is a detail in vertical section;

Figs. 5 and 6 are similar sections on the lines 5—5 and 6—6 of Fig. 9;

Fig. 7 is a rear elevation of the circuit breaker;

Fig. 8 is a vertical section through one of the fuse sockets;

Fig. 9 is a vertical section parallel to the face of the casing and taken approximately on the line 9—9 of Fig. 3;

Fig. 10 is an elevation from the rear of the snap mechanism for effecting a complete throw of the switch;

Fig. 11 is a diagram of the connections;

Figs. 12, 13 and 14 illustrate an alternative embodiment of the invention, Fig. 12 being a horizontal section and Figs. 13 and 14 being vertical sections on the correspondingly numbered lines of Fig. 12;

Figs. 15 to 18 illustrate another embodiment of the invention; Fig. 15 being a plan with the casing closed, Fig. 16 a plan of two fuses and a bridge inside the casing, Fig. 17 a longitudinal section with the casing open and Fig. 18 a side elevation of the upper part of the closed casing.

Referring to the embodiment of the invention illustrated there are provided in the cas-

ing fixed terminals 1, 2 (Fig. 11) for connection with the inside circuit 3 and with the coils 4 and 5 of the meter. The circuit passes from the coil 4 to a terminal 6 in the box, thence through a pair of blades 7 and 8 constituting a movable bridge to a terminal 9 which is connected to an outside main. The coil 5 of the meter is similarly connected through a terminal 10, terminals 11 and 12 constituting a bridge, and terminal 13 to the other main of the outside line. The movable bridges are mounted on the end of an arm 14 carried on a shaft 15 which may be operated to turn it to the circuit-breaking position at right angles to that shown.

The terminal 6 is in a plane outward from the plane of the terminal 9, and the blades 7 and 8 are similarly located (see Fig. 4); the relative positions being such that when the shaft is turned to the position shown in dotted lines in Fig. 9 the rear blade 7 will pass over or beyond the terminal 9 and avoid interference from this terminal. Similarly the terminals 10 and 13 on the opposite side and the corresponding blades 11 and 12 are in different planes, the rear blade 12 being beyond the plane of the terminal 10 so as to pass freely over it in the circuit-breaking movement. The lower blades 8 and 11 of the bridges swing in paths which overlie the lower portions of the fixed terminals 2, the positions of the blades 7 and 8 in the circuit-breaking position being indicated in dotted lines in Fig. 6, and the blade 7 being so far outward as to easily clear the high points of the terminal 2.

Fig. 9, for example, shows in full lines the circuits closed; and shows in dotted lines the blades 7, 8, 11 and 12 shifted to the circuit-breaking position. The cross-arm 14 which carries these bridges, carries also fuse sockets 16 and 17 (Fig. 3). One of these sockets 16 is shown in section in Fig. 8. The shell of the socket is in contact with the blade 12, and the central screw or pin 18 in the bottom of the socket is insulated from the shell and from the blade 12 and makes contact with the blade 11. When a fuse 19 is screwed into the socket the two parts 11 and 12 of the bridge are connected to each other. In a similar way the opposite fuse socket 17 is adapted to receive a fuse 20 which connects the two parts 7 and 8 of the bridge.

The fixed terminals are mounted on a block 21 of porcelain or other insulating ma-

terial which is supported on brackets 22 of sheet metal fixed on the back or base 23 of the casing. The lower end of the shaft 15 is rounded (Fig. 4) and projects through the block 21 and carries an arm 24 the end of which is bent outward and engages a link 25, Fig. 10, on the end of a tension spring 26 which is fixed at its opposite end to the rear face of the supporting block 21. This spring connection it a common expedient for effecting a complete throw of the shaft from the full line position, Fig. 10, to the dotted line position, so as to throw the switch completely to one or the other of the desired positions.

The box is formed with side walls 27 and end walls 28 with the usual or suitable provisions for forming openings for the passage of connectors of various kinds. A removable cover 29 is provided with flanges 30 fitting over the lower end and the sides. The upper end of the box has a flange 31 adapted to overlap the corresponding edge of the cover 29. The shaft extends outward through the cover and has a squared end adapted to receive the squared opening in the hub 32 of a handle 33 by which it is to be turned. The shaft is located within a spacer 34 which bears at its inner end against the adjacent part of a bushing in the block 21 and at its outer end against the intermediate part of the crossarm 14. Carried also on the squared end of the shaft is a circular plate 35. In fact the cross-arm 14, the plate 35 and the hub 32 of the handle are riveted to each other or otherwise fastened together as illustrated in Fig. 4; so that they are to be placed on the end of the shaft or withdrawn therefrom together.

The cover of the box is provided with diametrically opposite openings 36 and 37. The movable plate 35 is also formed with openings in line with the fuse sockets, as shown in Fig. 8 for the socket 16, and adapted to be brought into register with the openings 36 and 37 in the box cover when the switch is thrown entirely to the open position. Fig. 1 shows the holes closed by the plate 35, representing the closed position of the switch; and Fig. 2 shows the holes in the plate and the ends of the fuse sockets brought into register with the holes 36 and 37, the handle 33 having been turned to the position to open the circuit so that the fuses may be inserted without danger.

Fig. 8 shows the plate 35 formed with a depression 38 surrounding the opening 39 with which the socket registers, so that the head of the fuse 19 will be back of the cover 29 of the box. Also an annular strip 40 of insulating material is arranged around the edge of the opening 39 to prevent contact of the metal parts of the fuse with the plate

On the outer face of the cover 29 are perforated lugs 41 which register with a smaller lug or flange 42 carried by the hub plate 32 of the handle. By means of these lugs the handle is limited in its movement in each direction and it, and consequently the switch, can be locked in either of its two positions. A perforated lug 43 on the end of the box projects through an opening in the front plate 29 and serves to lock the latter in place.

The lever or handle 33 being unlocked, if a fuse blows out the operator turns to handle to the position of Fig. 2 exposing both fuse sockets simultaneously so that either or both can be provided with a new fuse. When the new fuse has been provided the handle is turned back to the position of Fig. 1, closing the circuit and at the same time preventing access to the fuse sockets.

The box cover 29 is formed with a central opening 44 which fits freely around the hub 32 of the handle, as shown in Fig. 4; and which is large enough to permit the withdrawal of the cover by first lifting the latter to the position shown in dotted lines at 29^a so as to free its upper edge from the flange 31, and then slipping it over the handle in the manner indicated in dotted lines at 29^b. Thereupon the handle together with the plate 35, cross bar 14, fuse sockets and blades carried thereby can also be lifted off the central shaft (first turning the shaft to disengage the blades from the terminals). This being done, the fixed terminals and supports are accessible.

The plate 35 is provided with small rounded outward projections 45 to provide a smooth bearing on the inner face of the cover 29. They may be applied with the same effect to the plate 58 of Figs. 12 and 13 and to the plate 66 of Fig. 17, herein-after described.

Fuse sockets or holding devices of various types may be substituted in place of those shown. Also various styles of circuit breaker may be used, and it is not essential that the fuse socket be interposed in the bridge or circuit breaker. Figs. 12, 13 and 14 illustrate a different construction in this respect. In the apparatus of these figures various details are omitted, the showing being directed to the circuit breaker and fuse construction.

The fuse sockets 46 and 47 are supported on insulated iron brackets 48, 49 mounted on the side walls of the box or casing. For each electric line there is a pair of insulated spring terminals 50 and 51 mounted on the base of the box. The terminal 51 is connected to the fuse casing as shown in Fig. 14. The screw 52 in the casing, suitably insulated from the latter and from the terminal 51, is connected to a terminal 53 spaced slightly above the terminal 50. The shaft

54, Fig. 12, carries a cross-arm 53 of insulating material on one end of which is a bridge or conductor 56 for connecting or disconnecting the line through the fuse and casing 46 and on the other end of which is a similar bridge 57 for connecting or disconnecting the line through the fuse and casing 47. In the positions shown (see Fig. 14) the bridge connects the respective terminals 50 and 53 of each pair and thus completes the circuit through each of the fuses in the sockets. When the shaft is turned at right angles this connection is broken.

The shaft carries a plate 58 turning with the shaft and lying back of the cover plate 29 of the box and having openings 59 which in the circuit closing position shown are out of register with the holes 60 of the box cover. When the shaft is turned to open the circuit the holes 59 in the plate are brought into register with the holes 60 of the cover, and thus provide access to the fuse sockets (which are in register with the holes of the cover) to permit withdrawal and insertion of either or both of the fuses 61, 62.

Figs. 15 to 17 illustrate a casing 63 of which the cover 64 is hinged so that it may be moved to open the box without entirely detaching it. The cover has a raised circular central portion with openings 65. These openings are controlled by a circular plate 66 pivotally mounted on the inside of the cover and having openings 67 which may register with the openings 65 of the cover or may be turned at right angles thereto so as to close the openings 65. The plate is formed with a handle 68 projecting through a slot 69 in the raised central portion 70 of the cover. The cover has its central portion offset to accommodate the movable plate and, in the particular design illustrated, to provide a space for the movable plate enclosed by a slotted wall through which the handle of the plate projects to the outside above the plane of the rest of the cover. On the latter are mounted stops 71, Fig. 15, which limit the angular movement of the handle 68 to the right or left and may serve also as locking posts. In the full line position shown the plate has uncovered the openings 65. If it be shifted around to the right against the opposite stop 71 the openings in the cover will be closed.

The fuse sockets 72 are mounted as shown in Figs. 16 and 17 on a cross-arm 73 which is fixed on the top of a shaft 74 which controls the movable bridges of the circuit as in Fig. 11; each of the fuse sockets carrying a fuse 75. The cross-arm 73 is in fact a plate of sheet metal with a flaring flange 76 around its edge, the ends being rounded so that said flange forms a pair of half round sockets into which fit the depending flanges or edges at the holes 67 in the plate 66.

When the cover is closed by pressing the plate down, and latching it with the spring latch 77 (Fig. 15), the flanges about the openings 67 fit within the flange 76 of the cross-arm 73. Then by throwing the 70 operating arm 68 to the right from the position of Fig. 15, the openings in the cover are closed as above described and at the same time the arm 73 is turned approximately 90 degrees so as to close the switches. 75

The principle of the invention may be applied to the control of a single line by using only one bridge or switch and one fuse, or may be applied to any number of lines. 80

While the invention is primarily useful where it is desirable to expose the fuse sockets through the cover of the casing, yet it may be used also where there is no such access through the cover and where the latter has to be removed or lifted before access can be had to the fuses; as for example where the electric company alone is to have access to the parts within the box. 85

In the present case the claims are directed 90 generically to the three alternative constructions illustrated and specifically to the form shown in Figs. 15 to 18; without, however, waiving the right to present specific 95 claims for the other forms in separate applications.

Though I have described with great particularity of certain specific embodiments of my invention, yet it is not to be understood therefrom that the invention is restricted to 100 the particular embodiments disclosed. Various modifications thereof in detail and in the arrangement of the parts may be made by those skilled in the art without departure 105 from the invention as defined in the following claims.

What I claim is:

1. A fuse switch mechanism including in combination a pair of switch terminals, a movable bridge for connecting said switch terminals and adapted to be disconnected from both of them, fuse terminals, a casing for said mechanism having a cover with an opening and a plate overlying said switch terminals and movable with said bridge and adapted to close the opening in the cover when the switch terminals are connected and to open it and permit replacement of a fuse when the switch terminals are disconnected. 110

2. A fuse switch mechanism including in combination a pair of switch terminals, a movable bridge for connecting said switch terminals and adapted to be disconnected from both of them, fuse terminals carried by said bridge, a casing for said mechanism having a cover with a flat portion in which is an opening, a plate overlying said switch terminals and carrying said bridge, said plate being mounted adjacent to the flat portion of the cover and movable in a plane 115 120 125 130.

- parallel thereto to permit the replacement of a fuse through said opening when the switch terminals are disconnected.
3. A fuse switch mechanism including in combination a casing with an opening therein, a plate rotatable on an axis perpendicular to the plane of the opening to cover or uncover said opening, a fuse socket, a switch and means adapted to move said plate to the uncovering position and at the same operation to open the switch.
4. A fuse switch mechanism including in combination a plurality of sets of circuit terminals, switches and fuses, one for each circuit, a casing normally preventing access to said parts and having openings through one of its walls and means rotatable in the plane of said openings for breaking the several circuit and rendering the several fuses replaceable at one time.
5. A fuse switch mechanism including in combination a shaft, a bridge carried thereby and a plate mounted on said shaft at right angles thereto and movable with said shaft adapted in the circuit-closing position of the bridge to prevent replacement of a fuse and in the circuit-breaking position to permit such replacement.
6. A fuse switch mechanism including in combination a casing with a movable cover having a flat portion in which is an opening, a plate movable in a plane parallel to the plane of said opening to cover or uncover said opening and a switch including a bridge movable with said plate and including fuse terminals, said plate and bridge being movable to permit replacement of a fuse between said fuse terminals when the cover is moved.
7. A fuse switch mechanism including in combination a casing with a movable cover having an opening, a plate movable to cover or uncover said opening, said plate having projecting points providing a bearing against the cover.
8. A fuse switch mechanism including in combination a casing with a movable cover, a switch within the casing and means accessible from the outside of the cover for operating said switch, said operating means adapted to be engaged with a part of the switch when the cover is in place and to be disengaged therefrom when the cover is moved from its closing position.
9. A fuse switch mechanism including in combination a casing with a movable cover, a switch within said casing, a pivoted cross bar by which said switch is actuated and a switch operating mechanism accessible from the outside of the cover and adapted to operatively engage said cross bar when the cover is in place and be disengaged therefrom when the cover is moved from its closing position.
10. A casing for mechanism of the character described, said casing having a cover with an opening for access to said mechanism, in combination with a plate movable in a plane parallel to the plane of the opening to cover or uncover said opening, said cover having an offset portion to accommodate the movable plate.
11. A casing for mechanism of the character described, said casing having a cover with an opening for access to said mechanism, in combination with a plate rotatable in a plane parallel to the plane of the opening to cover or uncover said opening, said cover having a circular portion offset and forming a circular recess in which said rotatable plate is located.
12. A casing for mechanism of the character described, said casing having a cover with an opening for access to said mechanism, in combination with a plate rotatable in a plane parallel to the plane of the opening to cover or uncover said opening, said cover having a circular portion offset outward and forming on its inner side a circular recess in which said rotatable plate is located with its handle projecting through a slot in the wall of the recess.

In witness whereof, I have hereunto signed my name.

THOMAS E. MURRAY.
